US0D1001320S

(12) **United States Design Patent** (10) **Patent No.:** **US D1,001,320 S**
(45) **Date of Patent:** **** Oct. 10, 2023**

(54) **ANCHOR COUPLER**

(71) Applicant: **Thomas Joseph Teffenhart, Jr.**,
Sarasota, FL (US)

(72) Inventor: **Thomas Joseph Teffenhart, Jr.**,
Sarasota, FL (US)

(**) Term: **15 Years**

(21) Appl. No.: **29/757,821**

(22) Filed: **Nov. 10, 2020**

3,382,639 A 5/1968 Smith et al.
3,413,775 A 12/1968 Katz et al.
3,566,561 A 3/1971 Tozer et al.
3,686,805 A 8/1972 Pofferi et al.

(Continued)

Primary Examiner — T Chase Nelson

Assistant Examiner — Sydney Margaret Parsley

(74) *Attorney, Agent, or Firm* — Jacox, Meckstroth & Jenkins

(57) **CLAIM**

The ornamental design for an anchor coupler, as shown and described.

DESCRIPTION

(62) Division of application No. 29/654,155, filed on Jun. 21, 2018, now Pat. No. Des. 919,420.

(51) **LOC (14) Cl.** **08-08**

(52) **U.S. Cl.**

USPC **D8/382; D25/133**

FIG. 1 is a front perspective view of an anchor coupler in accordance with another embodiment of the invention; FIG. 2 is rear perspective view of the anchor coupler of FIG. 1;

FIG. 3 is a top plan view of the anchor coupler of FIG. 1; FIG. 4 is a bottom plan view of the anchor coupler of FIG. 1;

FIG. 5 is a right side elevation view of the anchor coupler of FIG. 1;

FIG. 6 is a left side elevation view of the anchor coupler of FIG. 1;

FIG. 7 is a front elevation view of the anchor coupler of FIG. 1; and,

FIG. 8 is a rear elevation view of the anchor coupler of FIG. 1.

The broken dash dot lines shown in the figures are for the purpose of illustrating non-claimed portions and form no part of the claimed design. Neither the portions shown in broken dash lines nor the broken dash lines themselves form any part of the claimed design.

The broken dash lines shown in the figures are for the purpose of defining the bounds of the claimed design. The broken dash lines themselves form no part of claimed design.
